UNITED STATES PATENT OFFICE.

JOSEPH W. KENNA, OF CHICAGO, ILLINOIS, ASSIGNOR TO JAMES W. VAIL,
TRUSTEE, OF PORT WASHINGTON, WISCONSIN.

ТИЛТИНГ-ЧЕАР ИРОН.

SPECIFICATION forming part of Letters Patent No. 374,970, dated December 20, 1887.

Application filed September 22, 1884. Serial No. 143,638. (No model.)

To all whom it may concern:

Be it known that I, JOSEPH W. KENNA, a citizen of the United States, residing at Chicago, in the county of Cook and State of Illinois, have invented certain new and useful Improvements in Irons for Tilting-Chairs, of which I do declare the following to be a full, clear, and exact description, reference being had to the accompanying drawings, forming part of this specification.

My invention relates to that class of tilting-chair irons in which the spider-frame to support the chair-seat is pivotally joined to the vertical standard located at the upper end of the screw-spindle. An adjustable coil-spring located between the spider-frame and the standard serves to regulate the tilting movement about the pivotal connection.

The invention consists in certain novel combinations and arrangements of parts, hereinabove fully described, and particularly defined by the claims at the end of this specification.

Figure 1 is a view in side elevation, partly in vertical section, of the improved chair-irons, the seat and a portion of the base of the chair being shown attached thereto. Fig. 2 is a view of said irons, partly in vertical section and partly in side elevation. Fig. 3 is a rear view of the irons, parts being omitted for purpose of better illustration. Fig. 4 is a front view of the chair-irons, parts being omitted. Figs. 5, 6, and 7 are detail views of the washer at the front of the coiled spring. Figs. 8, 9, 10, and 11 are detail views of the washer at the rear of the coiled spring. Figs. 12, 13, and 14 are detail views of the pivotal plate against which the head of the adjusting-rod bears. Fig. 15 is a view in side elevation of a slightly modified form of my invention. Fig. 16 is a view in vertical longitudinal section of such modification. Fig. 17 is a front view, and Fig. 18 a rear view, of such modification.

A designates the base of the chair, to which is secured, in usual manner, the nut A', adapted to receive the spindle B. To the top of this spindle is connected what I designate the "standard" C, having the yoke-shaped arms c rising therefrom. These arms c are provided on their rear sides with the grooved lugs or seats c', and at their expanded tops are formed

with the shoulders c² c³, and with suitable perforations to receive the pivot-pin C'. A spider, D, having arms d, for attachment to the seat of the chair, is provided with the perforated lugs d', adapted to receive the pivot-pin C', with stops d² and d³, adapted to bear upon the shoulders c² c³ of the yoke-arms, and with the depending bearing-plate D', having the long slot d⁴ therein. This depending plate is formed of such shape and size, as shown, that when the several parts are in position for use it will be free to move between the yoke-arms of the standard.

Against the yoke-arms c bears the pivotal plate E, having the arms e, with inwardly-projecting ends arranged to fit within the seats c', and having the central squared perforation, e', adapted to receive the square end of the headed adjusting-rod F. This rod F passes through the slot d⁴ of the bearing-plate D', and upon it is held the coiled spring G, by means of the threaded hand-wheel H, which serves to regulate the tension of the spring. The inner end of this coiled spring fits over the hub i of the washer I, which rests against the bearing-plate D', and through the slot i' of this washer passes the adjusting-rod F.

Upon the rear side of the washer I are formed the pins i', adapted to fit corresponding depressions (seen in Fig. 4) in the bearing-plate D', and the shoulder i² of this washer is cut upon an incline to form a more even bearing for the end of the spring. Between the outer end of the coiled spring and the hand-wheel H is held the washer K, (seen in detail in Figs. 5, 6, and 7,) having the hub k, over which the spring fits, and having the inclined shoulder k', to form a seat for the end of the spring.

When the several parts are in position for use, they will be relatively arranged as shown in Figs. 1 to 4 of the drawings. The force of the coiled spring will retain the chair-seat normally in horizontal position; but when sufficient pressure is exerted to tilt the chair the depending bearing-plate D' will swing slightly forward between the yoke-arms c, thus tending to compress the spring, the tension of which can be controlled at will by the adjustment of the hand-wheel H.

It is to be noted as an important feature of

my present invention, and one which I desire to claim broadly, that the pivotal plate E serves to sustain the adjusting-rod in such manner that this rod can shift with the tilting movement of the chair, and hence all strain upon the rod, and consequent danger of breakage, is avoided.

It will also be observed that by forming the rod with a squared end fitting within a correspondingly squared opening of the pivotal plate this plate prevents the turning of the rod when the hand-wheel is turned to regulate the tension of the coiled spring.

In the modified construction illustrated in Figs. 15 to 18 it will be seen that the coiled spring bears against the bearing-nut W, which bears against the face of the depending plate D', which in this instance is upon the front side of the standard. The standard below its pivot-arms is furnished with a perforation to receive the adjusting-rod F, and upon its back with a suitable seat for the pivotal plate E. The end of the slot in the depending plate striking the adjusting-rod limits the forward movement of the chair seat, and suitable stops or shoulders, w, on the spider and standard restrict its backward movement.

By the construction and arrangement of parts in the manner above stated a simple, cheap, durable, and effective tilting mechanism for chairs is secured.

I am well aware that in Wolff's Letters Patent No. 197,195, November 13, 1877, for tilting-chairs, there is shown a pivot-plate at the terminus of and in piece with the adjusting-rod; but said plate seats against the radially-moving dependent lugs or extensions of the tilting spider-frame, and not against the fixed standard, as in my construction. The coil-spring is permanently set upon the standard, and, together with the rod, has a strictly rectilinear play during the tilting movement, whereas in my device the spring and rod are constantly subjected to a radial shift or strain, which it is the function of the pivot-plate to compensate and readjust. Obviously the organization of the parts and the mode of operation are markedly different in the Wolff patent from that which I employ. In my former Letters Patent, No. 294,391, March 4, 1884, the construction of the parts more nearly resembles the present invention; but the adjusting-rod is fixed rigidly to the standard, and not pivotally set thereon, as by my improvement. Both rod and coil-spring are consequently subjected to strain and disarrangement during the tilting play, to remedy which is one purpose of my invention.

The general combination, with a spider-frame and a vertical standard about which said frame tilts, of an adjustable coil-spring pivotally set and mounted substantially at its end faces between the spider and standard, respectively, to control the tilting movement, is no part of the present invention; nor does

the same involve the presence in such combination of a bearing-nut mounted upon the adjusting-rod and having a spiral-like face to seat one end of the pivotal and adjustable coil-spring. These features of organization are made the subject of claims in a separate application, which has been filed by me prior hereto, dated September 15, 1884, Serial No. 143,149.

Having thus described my invention, what I claim as new, and desire to secure by Letters Patent, is—

1. In tilting-chair irons, the combination, with the spindle and the standard having the pivot-arms, of the spider pivoted to said arms, and having a downwardly-projecting bearing-plate for the spring, an adjusting-rod, a pivotal plate to sustain said rod and set against the standard, a coiled spring, and an adjusting hand-wheel, substantially as described.

2. In tilting-chair irons, the combination of the spindle, the standard having yoke-shaped arms, the spider pivoted to said standard, and having the slotted depending bearing-plate, of a size permitting it to move between the yoke-arms of the standard, the adjusting-rod, the pivotal plate having arms, substantially as described, bearing against the yoke-arms of the standard, the coiled spring extending beneath the front portion of the chair-seat, and the adjusting hand-wheel, substantially as described.

3. In tilting-chair irons, the combination, with the standard, a spider pivoted thereto, a coiled spring, and an adjusting-rod and hand-wheel, of a pivotal plate bearing against the standard and sustaining the adjusting-rod, substantially as set forth, whereby said rod accommodates itself to the radial shift of the spider, substantially as described.

4. In tilting-chair irons, the combination, with the standard, a spider pivotally secured thereto, a coiled spring, and an adjusting-rod having a square portion and hand-wheel, of a pivotal plate having a squared opening through which the squared end of said rod passes, and which serves to prevent the turning of the rod with the adjusting-wheel, substantially as described.

5. In tilting-chair irons, the combination, with the standard, of the spider-frame pivoted thereto and having the depending bearing-plate, a coil-spring, an adjusting-rod sustained by said standard, a hand-wheel, and a bearing-nut to receive the end of the coil-spring, said nut resting against the face of the plate depending from the spider-frame, substantially as described.

In testimony whereof I have hereunto set my hand this 18th day of September, 1884.

JOSEPH W. KENNA.
